(57) **CLAIM**

The ornamental design for an extender port for making optical connections, as shown and described.

DESCRIPTION

FIG. 1 is a front perspective view of an extender port for making optical connections showing our new design; FIG. 2 is a front view thereof of FIG. 1; FIG. 3 is a rear view thereof of FIG. 1; FIG. 4 is a right side view thereof of FIG. 1; FIG. 5 is a left side view thereof of FIG. 1; FIG. 6 is a top view thereof of FIG. 1; and, FIG. 7 is a bottom view thereof of FIG. 1.

In FIGS. 1, 4, 5, and 6, the broken lines represent the bounds of the claim and form no part of the claimed design.

1 Claim, 5 Drawing Sheets
